UNITED STATES PATENT OFFICE.

JOHN SQUIRES, OF DETROIT, MICHIGAN.

HOOD-RETAINER FOR MOTOR-VEHICLES.

Specification of Letters Patent. Patented July 11, 1916.

1,190,603.

Application filed May 8, 1916. Serial No. 96,039.

To all whom it may concern:

Be it known that I, JOHN SQUIRES, a citizen of the United States, and residing at Detroit, in the county of Wayne and State 5 of Michigan, have invented a new and Improved Hood-Retainer for Motor-Vehicles, of which the following is a specification.

This invention relates to means for yieldingly holding down or retaining the lower 10 edges of the hoods of motor vehicles, and its object is to provide devices of this character which will be strong, simple, and easily attached to and detached from the hood, and which will prevent rattling 15 cause of the uniform downward pull on the lower edges of the hood.

This invention consists of a substantially C shaped spring having one end pivotally mounted on a side bar of the chassis or 20 frame of the vehicle, a hook or pair of hooks secured to the adjacent side of the hood, and a pin or cross bar connecting the free end of said spring to the hook on the hood.

In the accompanying drawing Figure 1 is 25 a side elevation of the hood of a motor vehicle equipped with this improved retainer. Fig. 2 is an end elevation and Fig. 3 a side elevation of this retaining device. Fig. 4 is an elevation of a connecting pin.

Similar reference characters refer to like 30 parts throughout the several views.

In the drawings, 1 is a side bar of the chassis or frame which supports the radiator 2 and the dash 3. The hood 4 may be 35 of any desired construction and it normally rests on the dash and on a flange 5 projecting rearwardly from the radiator. These parts are shown conventionally and any other construction of hood, dash and radiator may be employed.

The retaining device for holding down the lower edge of the side 6 of the hood consists of a bracket 7 secured to the side bar 1 by means of bolts 8. The two eyes 9 on this 45 bracket receive the pin 11 having a groove 12. A C-shaped resilient member 13 formed from a flat bar has an eye 14 at each end, and each eye is formed with an inwardly extending tongue 15 that projects into the groove 12 in the pin 11.

Secured to the side 6 of the hood by means of the bolts 16 is a plate 17 having hooks 18 that are adapted to receive the pin 11 at the free end of the resilient member 13. To assemble the retainer, the lower end of the 55 resilient member is placed between the eyes 9 of the bracket 7 and a pin 11 is driven through the aligned eyes, the rounded ends of the pin 11 forcing back the tongue 15 which later on snaps into the 60 groove 12 and thus locks this pin in proper position. The other pin is similarly driven into the eye at the free end of the resilient member 13 and is held in central position by the tongue 15 at that end. When the 65 plate 17 and bracket 7 are secured in place, and the hood has been closed, the resilient member is sprung open from the position shown in dotted lines in Fig. 2 to beyond that shown in solid lines, and the pin 11 at 70 the free end of the member 13 is guided so as to lodge in the hooks 18, the resiliency of the member 13 thereafter serving to press down the side 6 of the hood.

While two resilient hood retainers are 75 shown in Fig. 1, it must be understood that any desired number may be mounted at each side of the hood. The details and proportions of the various details may all be changed without departing from the spirit 80 of my invention as set forth in the claims.

I claim:

1. In a motor vehicle, the combination of a frame and a hood, a bracket secured to the frame and carrying a pin, a C-shaped resilient member, pivotally mounted on said pin, a hook secured to the hood, and a pin carried by the free end of the resilient member and adapted to engage said hook.

2. In a motor vehicle, the combination of 90 a frame and a hood, a C-shaped resilient member, means at one end of the resilient member connecting it to the frame and at the other end connecting it to the hood, said resilient member being stressed so as 95 to press the hood toward the frame.

3. In a motor vehicle, the combination of a frame and a hood, a bracket secured to the frame, a pin mounted in the bracket, a pair of hooks secured to the hood, a resilient 100

member formed from a flat bar bent to substantially C-shape having one end wound around said pin carried by the bracket, and a second pin around which the free end of the resilient member is wound and which is adapted to be engaged by the hooks on the hood, one of said pins having a circumferential groove intermediate its ends, said resilient member being formed with a tongue struck up from the portion wound around said pin to enter said groove and prevent longitudinal movement of the pin.

JOHN SQUIRES.
